UNITED STATES PATENT OFFICE

104,661

DESIGN FOR A DESK STAND

Benjamin W. Hanle, Elizabeth, N. J., assignor to Eagle Pencil Company, New York, N. Y., a corporation of Delaware

Application March 26, 1936, Serial No. 61,791

Term of patent 7 years

To all whom it may concern:

Be it known that I, Benjamin W. Hanle, a citizen of the United States of America, residing at 390 Springfield Road, city of Elizabeth, State of New Jersey, have invented a new, original, and ornamental Design for a Desk Stand, of which the following is a specification, reference being had to the accompanying drawing, forming part thereof, in which

I claim:

The ornamental design for a desk stand, as shown.

BENJAMIN W. HANLE.
